(57) CLAIM

We claim the ornamental design for a hand brush handle, as shown and described.

DESCRIPTION

FIG. 1 is a perspective view of the hand brush handle
showing our new design;

FIG. 2 is a front elevational view of the hand brush handle,
the rear elevational view being a mirror image;

FIG. 3 is a top plan view of the hand brush handle;

FIG. 4 is a bottom plan view of the hand brush handle;
and,

FIG. 5 is a left elevational view of the hand brush handle;
and,
FIG. 6 is a right elevational view of the hand brush handle.
The broken lines shown are for illustrative purposes only and form no part of the claimed design.
